UNITED STATES PATENT OFFICE

99,272

DESIGN FOR A COAT OR SIMILAR ARTICLE

Abraham Dufine, New York, N. Y., assignor to
Sherman Bros. Rainwear Corp., New York,
N. Y., a corporation of New York

Application November 4, 1935, Serial No. 59,368

Term of patent 3½ years

To all whom it may concern:

Be it known that Abraham Dufine, a citizen of the United States and resident of New York city, county of New York, State of New York, has invented a new, original, and ornamental Design for a Coat or Similar Article, of which the following is a specification, reference being had to the accompanying drawing, forming part thereof, in which,

Fig. 1 is a front perspective view of a coat showing my design, the hood being in an elevated position.

Fig. 2 is a rear perspective view of the coat shown in Fig. 1 showing the hood thrown back, forming a cowl collar.

Fig. 3 is a front perspective view unbuttoned, with one side of the coat drawn back showing the zippered pocket on the inside, and the hood thrown back off the head; and

Fig. 4 is a perspective rear view of the upper portion of the coat, with the hood in a raised position.

The characteristic features of the design reside in the coat having a widely flaring cape with widely overlapping portions at the front buttoned together, with said cape having seams meeting at the shoulders and extending to the bottom of the cape, and with the hood buttoned to the collar of the cape, which hood may be thrown back off the head to simulate a cowl collar, and the inside zippered pocket at the bottom end of one of the armholes.

I claim:—

The ornamental design for a coat or similar article, substantially as shown and described.

ABRAHAM DUFINE.
